UNITED STATES PATENT OFFICE.

GEORGE G. FLOYD, OF GRANITE CITY, ILLINOIS, ASSIGNOR TO AMERICAN STEEL
FOUNDRIES, OF NEW YORK, N. Y., A CORPORATION OF NEW JERSEY.

CAR-TRUCK.

973,024.

Specification of Letters Patent. Patented Oct. 18, 1910.

Application filed October 28, 1909. Serial No. 525,027.

To all whom it may concern:

Be it known that I, GEORGE G. FLOYD, a citizen of the United States, residing at Granite City, in the county of Madison and 5 State of Illinois, have invented certain new and useful Improvements in Car-Trucks, of which the following is a specification.

This invention relates to improved and novel means in railway car-truck constructions which will permit the ready and easy removal of the bolster lengthwise through its aperture of the side-frame. Many and various schemes have been provided for reaching this desired result, but I believe that 15 the present invention provides a construction possessing several features and characteristics of novelty and improvement. In accordance with this idea, the columns of the side-frames, instead of being cast integrally with therewith, are made separate and are so connected to the side-frames that they may be shifted therein without actual removal to permit the lengthwise withdrawal of the bolster; or, if desired, these columns may 25 be wholly taken out of the side-frames. In one embodiment of the invention the sides of the side-frame bordering the bolster aperture are provided with vertical under-cut 30 grooves to accommodate correspondingly-formed columns, such grooves or recesses extending upwardly through the top of the side-frame to permit insertion of the columns, the latter resting on the lower ends of the grooves or recesses so as to be supported 35 thereby.

From a consideration of the detailed description of a preferred embodiment of the invention set forth below, which should be read in connection with the accompanying 40 drawing forming a part of this specification, it will be apparent that a car-truck including this invention is simple in construction, economical to manufacture, and renders possible the desired results stated above.

45 In this drawing—Figure 1 is a side elevation of a car-truck with parts omitted and the side-frame shown partially in section; Fig. 2 is a partial plan and partial horizontal section on line 2—2 of Fig. 1; Fig. 50 3 is a central vertical cross-section through the side-frame with the columns omitted; and Fig. 4 is a perspective view of one of the removable or shiftable columns.

By reference to the drawing it will be 55 noted that the bolster 10 has on opposite

faces of its end portion the spaced column guides 11, 11 providing between them grooves or recesses 12 to accommodate the columns. The side-frame 13 has the usual central opening 14 for the reception of the 60 spring-plank 15, springs 16, and the end of the bolster. In the present instance this opening or aperture is of substantially rectangular form, being bounded by the opposite side walls 17 and 18, which at their 65 lower ends are composed of transverse flanges, their upper ends or portions being considerably thickened as at 19 and supplied on their adjacent faces with vertical centrally-disposed undercut grooves 20 terminating at the top of the lower flange portions of such walls at 21, whereby to provide 70 seats or supports for the vertical removable or shiftable columns or bolster guides 22 in cross-section of substantially I-form, whereby their lateral disengagement from such 75 grooves is prevented. The portions of such columns or guides protruding into the bolster aperture 14 of the side-frame, as will be readily understood, form the columns or 80 guides for the bolster and are intended to fit in the above-mentioned grooves or recesses 12 of such bolster. The recesses 20 extend upwardly through the top compression 85 member 23 of the side-frame, the latter completely encircling the top ends of such removable or shiftable columns or guides because of the bosses or enlargements 24 formed on the lower part of such compression member. In order to prevent upward 90 shifting or displacement of such columns or guides each is provided or supplied with a hole 25 extended therethrough near its upper end and adapted to receive a pin 26 passing through holes 27 of the side-frame registering with the aperture 25. Such pins are, 95 of course, readily and easily removable to permit the taking out or upward withdrawal of such disengageable columns or guides. As is indicated, the aperture 14 of the side-frame would be ordinarily constructed of substantially the same width as the over-all transverse dimension of the bolster over its 100 column guides 11.

The removal or withdrawal of the bolster 105 is effected in substantially the following manner: The spring 16 having been taken out, the bolster may be either permitted to descend or may be maintained in the normal position shown in Fig. 1. In any case, the 110

shiftable columns 22, after the pins 26 have been removed, are pushed upwardly, or wholly removed from the side-frame if desired, so as no longer to reside in the guiding grooves 12 of the bolster, and in such position of the parts the bolster is free to be withdrawn longitudinally laterally of the truck through the opening 14 of the side-frame, as is customary in other constructions 10 of this general character.

The manner in which a bolster would be placed in the truck and the columns brought to proper position is obvious from the above description of its removal and needs no detailed explanation.

I do not wish to have it understood that this invention is limited to the particular embodiment illustrated on the drawings and described in this specification, because the 20 invention is capable of a considerable number of embodiments differing more or less in structural characteristics, each of such embodiments possessing the features of advantage and improvement inherent in the invention.

I claim:

1. In a railway car-truck, the combination of a bolster, a side-frame having an aperture for the accommodation of the end of

the bolster, the parts of the side-frame constituting the side-walls of said aperture being grooved, and columns with which the bolster column guides are adapted to co-operate shiftably mounted in said grooves, there being a projection and recess connection between each column and one of the walls of the groove, whereby when said columns are moved out of normal position the bolster may be taken out lengthwise through the side-frame aperture, substantially as described.

2. In a railway car-truck, the combination of a bolster, a side-frame having an aperture for the accommodation of the end of the bolster, the portions of said side-frame forming the side-walls of said aperture being provided with vertical under-cut grooves, and columns with which the bolster column guides are adapted to co-operate shiftably mounted in said under-cut grooves, whereby when they are moved out of normal position the bolster may be taken out lengthwise through the side-frame aperture, substantially as described.

GEORGE G. FLOYD.
